UNITED STATES PATENT OFFICE.

PERCY SIMPSON, OF LONDON, ENGLAND.

PRINTER'S COMPOSING STICK.

Application filed May 5, 1923. Serial No. 637,027.

To all whom it may concern:

Be it known that I, PERCY SIMPSON, a subject of the King of Great Britain, and resident of Bowling Green Lane, Farringdon Road, London, E. C. 1, England, have invented certain new and useful Improvements in Printers' Composing Sticks (for which I have filed an application in England dated 9th November, 1922), of which

10 the following is a specification.

This invention relates to composing sticks. In all sticks such as hitherto constructed there have been projecting rough parts which are found in use to chafe the hands of the 15 compositor. In some previous constructions the knee has been clamped by means of a screw or bolt projecting from it at the longitudinal edge of the base plate and in others notches have been formed in a projecting 20 part of the stick, for example, the top edge of the back flange leaving projecting teeth. It is the chief object of the present invention to provide a composing stick which shall have no projecting parts which are 25 liable to chafe or otherwise injure the compositor's hands.

According to the present invention, a spring pressed bolt or the equivalent is mounted to slide in the cross member of the 30 knee or slide and is pressed resiliently outwards. This bolt is extended around the longitudinal edge of the base plate and passes under the latter and is formed with teeth which engage in notches formed on the 35 inner edge of a part of the base plate turned down and under the main base plate. The resilient pressure on the bolt, therefore, holds the turned down part of the bolt in engagement with these notches.

40 In order that the invention may be clearly understood and readily carried into effect, an example of a composing stick constructed in accordance therewith will now be more fully described with reference to the accompanying drawings, in which:—

Figure 1 is a front elevation of the stick; Figure 2 a rear elevation; and

Figure 3 a cross section on the line III—III of Figure 1.

50 The base plate *a* has a portion *b* turned down along its longitudinal edge and folded upon itself below the base plate *a* as seen in Figure 2. The actual edge of the folded over portion *b* is formed with a number of notches *c* leaving relatively blunt teeth.

55 The cross member of the knee or slide *d*

is drilled longitudinally as seen in Figure 3 and within it slides a spring pressed bolt *e*. The head *f* of this bolt is extended around the longitudinal edge of the base 60 plate *a* and the folded over portion *d* and is formed on its inner surface *g* with teeth adapted to engage in the notches *c*. Under normal conditions the teeth are caused to engage the notches *c* by the coiled compression spring *h* located within the bore in the slide *d* and tending to press outwards the bolt *e* so that this bolt serves as a catch to maintain the slide *d* in any position in which it has been set. The longitudinal edge of 65 the base plate *a* is furnished with an engraved scale *k*, as is usual and the graduations of this scale correspond with the width of the notches *c*. The longitudinal edge of the base plate is usually the weakest part 70 of a composing stick because it is subjected to bending stresses when in use. The improved method of folding over this edge considerably stiffens it against bending and consequently the base *a* as a whole can be 75 made of thinner metal reducing the weight of metal in the whole stick and rendering the latter easier to handle while maintaining its efficiency with regard to durability.

In order to make an adjustment of the 80 stick, it is merely necessary for the compositor to press on the head *f* of the bolt or catch *e* so as to compress to a small extent the coiled spring *h* and to push the toothed turned-over part of the head *f* out of engagement with the notches *c*. The knee or slide *d* is then free and can be moved along the stick to the desired position when the bolt head *f* is again released and engages 85 the notches *c*. As can be seen from Figure 90 1 the head *f* is in such a position that the compositor can release it merely by pressure of his thumb so that the slide *d* is released more easily and more quickly than in previous forms of stick and in the present case 95 the stick can be re-adjusted without alteration of the position of the compositor's hand.

The slide *d* is formed with a right angled portion *l* which rests in contact with the inner face of the back flange *m* of the stick. As illustrated also a clamp *n* is provided to embrace the back flange *m* and the part *l* of the slide. Such a clamp which is not novel in itself is shown turned under the 105 base plate at *o* and engaging the inner surface of the part *l* of the slide *d*. A screw 110

with a milled head *p* is shown passing through the clamp *n* and it can be screwed up until its point bears on the part *l* of the slide *d*. This clamp is arranged so that it 5 does not provide any harmful projecting parts. The part of the clamp *n* embracing the back flange *m* is made quite smooth and the screw *p* projects across the top of the base plate *a* and is therefore not in a position to interfere with the use of the stick. 10

Having thus described my invention what I claim as new and desire to secure by Letters Patent is:—

1. In a printer's composing stick, a base 15 plate having a longitudinal edge folded under upon itself and formed with teeth along said edge, an adjustable knee slidably mounted on said base plate, a catch mounted to slide laterally in said knee and having a 20 head co-operating with said teeth and resilient means for holding said head in engagement with said teeth.

2. In a printer's composing stick, a base 25 plate having a longitudinal edge turned down and folded upon itself and formed with teeth along said edge, an adjustable knee slidably mounted on said base plate and having a lateral bore, a catch with a cylindrical shank slidably mounted in said bore 30 and with a head turned over to engage said teeth and a coiled compression spring lodged within said bore and resiliently pressing said catch outwards to maintain its head in engagement with said teeth.

3. In a printer's composing stick, a base 35 plate with a stiffened longitudinal edge turned down and folded upon itself and formed with teeth along said edge, an ad-

justable knee slidably mounted on said base plate and a catch mounted in said knee in 40 position to engage said teeth and arranged to be disengaged by pressure of the operator's thumb.

4. In a printer's composing stick, a base 45 plate having a stiffened longitudinal edge turned down and folded upon itself and formed with teeth along said edge and a flange along the back longitudinal edge, an adjustable knee slidably mounted on said base plate and formed with a cross member 50 and a longitudinal member in contact with said flange, a sliding catch mounted in the cross member of said knee and shaped to engage said teeth, a spring in operative relation with said catch for maintaining the latter in engagement with said teeth and a screw clamp for clamping said knee to said flange.

5. In a printer's composing stick, a base 60 plate with a stiffened longitudinal edge turned down and folded upon itself and formed with teeth along said edge and a flange along the back longitudinal edge, an adjustable knee slidably mounted on said base plate and formed with a cross member 65 and a longitudinal member lying in contact with the flange of said base plate, a catch having a cylindrical shank slidably mounted in a bore in said cross member and a head 70 extended around said stiffened edge to engage said teeth, a coiled compression spring lodged in said bore to press upon said catch to maintain it in engagement with said teeth and a smooth screw clamp for clamping said knee against the flange of said base plate.

PERCY SIMPSON.
